KITE

Manuel Carrasco, New York, N. Y., assignor of
one-half to William Recht, Woodmere, N. Y.

Application May 13, 1939, Serial No. 273,407

11 Claims. (Cl. 244—153)

My invention relates to kites of the type comprising a wing having substantial area.

My invention has further reference to a kite comprising a wing above which a rotor is supported for free rotatable movement.

My invention has further reference to a kite of the character described having a readily detachable rotor and a foldable rotor support.

Various other objects, advantages and features 10 of my invention will become apparent from the following description.

My invention resides in the kite, rotor kite, features and combinations of the character hereinafter described and claimed.

15 For an understanding of my invention and for an illustration of some of the many forms thereof, reference is to be had to the accompanying drawing, in which:

Figure 1 is a plan view of a kite as constructed 20 in accordance with my invention;

Fig. 2 is a side elevational view, partly in section, of the kite shown in Fig. 1;

Fig. 3 is an enlarged elevational view, partly 25 in section, showing the foldable support for the kite rotor;

Fig. 4 is an enlarged elevational view, partly 30 in section, showing the rotor support in folded position;

Fig. 5 is a plan view, partly broken away, of a 35 rotor blade;

Fig. 6 is an elevational view, partly in section, taken on the line 6—6 of Fig. 5 looking in the direction of the arrows;

Fig. 7 is an elevational view, partly in section, taken on the line 7—7 of Fig. 5 looking in the direction of the arrows;

Fig. 8 is a perspective view showing detached parts of a rotor bearing;

Fig. 9 is a horizontal sectional view taken on the line 9—9 of Fig. 8 looking in the direction of the arrows;

Fig. 10 is a perspective view showing a modified rotor support; and

Fig. 11 is a vertical sectional view, partly in elevation, taken on the line 11—11 of Fig. 10.

Referring particularly to Fig. 1, the kite of my invention comprises a wing W having substantial area which acts as a supporting or elevating surface while the kite is in the air. The wing W may be of any suitable shape or configuration and, as a preferred arrangement, it comprises a longitudinal member 1 and a transverse member 2, the latter, preferably, being of curved configuration and symmetrically arranged with 50 respect to the longitudinal member 1, adjacent

surfaces of the members 1 and 2, preferably, being suitably secured together, as by adhesive locally applied or otherwise as may be desirable.

The frame formed by the members 1 and 2 serves as a support for a sheet 3 of paper, treated fabric, or equivalent wing material which should be adhesively or otherwise suitably secured to said frame members 1 and 2. At the ends of the frame members 1 and 2, tabs 4 may be adhesively secured to adjacent surfaces of the sheet 1 and the respective frame members so as to more securely retain the sheet 1 in proper position. The edges of the sheet 3 may be folded as indicated at 5 and the folded edges adhesively secured to the adjacent sheet surfaces. If desired, a wire or string, not shown, of small diameter may extend around the outer surfaces of the wing W between the above noted folded edges thereof.

In accordance with the invention, the frame 20 formed by the members 1 and 2 carries a support for a suitable rotor R having any desired number of blades. As herein shown, this rotor support is of tripod configuration in the sense that it is formed from three members 6, 7 and 8, the members 6 and 7, preferably, being pivoted to the frame member 2 equi-distantly from the member 1 and the member 8, preferably, being pivoted to the frame member 1. Any suitable pivotal arrangement may thus be utilized for 25 each of the members 6, 7 and 8. As shown in Figs. 3 and 4 with respect to the members 1 and 2, each pivotal arrangement may comprise a wire 9 which is disposed around the frame member 1 and which extends through an opening formed 30 in a flange forming part of a collar 10 secured to the member 8.

When the members 6, 7 and 8 are positioned as shown in Figs. 1, 2 and 3, the upper flat ends thereof are disposed against the respective flat sides 11a of a structure 11, the lower end of which is threaded for the reception of a sleeve nut 12 which serves to detachably clamp the upper ends of the members 6, 7 and 8 to the structure 11. Upstanding from the structure 11 is a pin or spindle 13 which forms an axle for retaining the rotor R on the bearing formed by the conical upper part of the structure 11, the spindle 13 being inclined to the plane of the wing W so that the rotor R is similarly inclined. As 45 shown in Fig. 8, the pin 13 is threaded for the detachable reception of a nut 14 which may have a conical surface facing the conical bearing of the structure 11.

The rotor R may assume any one of a variety 55

of forms. As shown in Figs. 1, 2, 3 and 5, said rotor R comprises a pair of cardboard or equivalent disks 15, 15a disposed in facing relation, these disks being adhesively or otherwise suitably secured together so as to form a rigid structure. Preferably, a block 16 is secured to the disks 15, 15a at the center thereof, a passage being provided through this block 16 and the disk 15a for loosely receiving the pin 13.

10 The rotor blades may be of any suitable form. As herein shown, each rotor blade comprises a rod 17 having a plurality of spaced members 18 secured thereto in transverse relation, all of the members 18 of each rotor blade being disposed substantially in a single plane which may be curved. The frame formed by each rod 17 and the associated members 18 serves as a support for a sheet 19 of paper, treated fabric or the like which should be adhesively or otherwise suitably secured to the associated rod 17 and members 18. Preferably, the sheet 19 is of double thickness as indicated in Fig. 5 and, if so, the marginal edges thereof removed from the rod 17 should be adhesively secured together as indicated at 19a. 15 20 comprising a plurality of members extending upwardly from said wing, means for supporting said members so they may be collapsed, and a rotor freely rotatable on said support when it is in upstanding relation.

5 6. A kite adapted to be controlled during flight by a string or the like, said kite comprising a wing having substantial area, a rotor support comprising a plurality of members extending upwardly from said wing, means for supporting said members so that they may be collapsed toward said wing, and a rotor freely rotatable on said support when it is in upstanding relation.

10 7. A kite adapted to be controlled during flight by a string or the like, said kite comprising a wing having substantial area, a rotor support comprising a plurality of members extending upwardly from said wing, means for supporting said members so that they may be collapsed, means 15 for retaining said members in upstanding relation with respect to said wing, and a rotor freely rotatable on said support when it is in upstanding relation.

20 8. A kite adapted to be controlled during flight by a string or the like, said kite comprising a wing having substantial area, a rotor support comprising a plurality of members extending upwardly from said wing, means for supporting

said members so that they may be collapsed toward said wing, means for retaining said members in upstanding relation with respect to said wing, a bearing carried by said rotor support, and a rotor detachably carried by said bearing.

25 9. A kite adapted to be controlled during flight by a string or the like, said kite comprising a wing having longitudinal and transverse frame members, a rotor support adapted to extend upwardly from said wing, said rotor support comprising members pivoted to said frame members, means for retaining said members in upstanding relation with respect to said wing, a bearing carried by said rotor support, and a rotor detachably carried by said bearing.

10 10. A blade for the rotor of a kite, said blade comprising a rod, supports extending transversely of and secured to said rod, and a surface of sheet-like material adhesively secured to said rod and supports.

15 11. A blade for the rotor of a kite, said blade comprising a rod, supports extending transversely of and secured to said rod, and a double-thickness surface of sheet-like material adhesively secured to said rod and supports, the width of 20 said surface decreasing toward the ends of said rod.

MANUEL CARRASCO.
